UNITED STATES PATENT OFFICE.

CHARLES L. GOODRUM, OF BROOKLYN, NEW YORK, AND JOHN A. KROPP, OF OAK PARK, ILLINOIS, ASSIGNEES TO WESTERN ELECTRIC COMPANY, INCORPORATED, OF NEW YORK, N. Y., A CORPORATION OF NEW YORK.

SELECTING-SWITCH.

1,286,996.

Specification of Letters Patent.

Patented Dec. 10, 1918.

Application filed October 13, 1916. Serial No. 125,463.

To all whom it may concern:

Be it known that we, CHARLES L. GOODRUM and JOHN A. KROPP, citizens of the United States, residing at Brooklyn, in the county of Kings and State of New York, and at Oak Park, in the county of Cook and State of Illinois, respectively, have invented certain new and useful improvements in Selecting-Switches, of which the following is a full, clear, concise, and exact description.

This invention relates to selecting switches of the two-movement type.

The purpose of the present invention is the production of a switch utilizing a single motor for actuating the switch in its several movements to place the active contacts of the switch into engagement with the desired passive contacts.

In the specific embodiment of the invention herein disclosed, the operating motor is actuated on the restoration of the switch to its normal position to store up energy for the next operation of the switch.

Referring to the drawings, Figure 1 is a side elevation of the switch, with portions broken away for clearness in illustration; Fig. 2 is a front elevation of the lower portion of the switch; Fig. 3 is a sectional plan view taken on the line 3-3 of Fig. 2; Fig. 4 is a sectional view taken on the line 4-4 of Fig. 1; Fig. 5 is a plan view taken on the line 5-5 of Fig. 1; Fig. 6 is a plan view partly in section taken on the line 6-6 of Fig. 1; Fig. 7 is also a plan view taken on the line 7-7 of Fig. 1.

Referring in detail to the drawings, 10 designates a brush-carrying element or shaft mounted for vertical and rotary movement in a frame (not shown). This shaft 10 carries brushes 11, which engage contacts 12 of a switch bank 13. The shaft, near its intermediate portion, is provided with vertical ratchet teeth 14, which are engaged by a vertical escapement member 15 carried by the armature 16 of a vertical magnet 17. The shaft is also provided with rotary ratchet teeth 18, which are engaged by the rotary escapement member 19 carried by the armature 20 of a rotary magnet 21.

40 The switch is provided with a spring motor which is rewound each time that the

switch is restored to its normal position. This spring motor, the details of which are herein later described, actuates the shaft in its upward vertical and rotary step-by-step 55 movements which are controlled by the vertical and rotary escapement members 15 and 19.

A cylindrical member 22 provided with a notched flange 23 and a rectangular opening, is mounted to rotate on the shaft and is attached at 24 to a spiral spring 25. This spring is coiled about the vertical shaft and has its other end attached to a collar 26, which is securely attached to the shaft. A 60 pin 26' carried by collar 26 operates in the rectangular opening in member 22 to limit the rotary movement of this member with respect to the shaft. The cylindrical member is also provided with a spiral groove in 70 which a pin 27 carried by an arm attached to the armature 28 of release magnet 29, rides to wind up the spring. A vertical guide rod 32 carried by the frame, serves as a stop against which an arm 33 attached to 75 the cylindrical member engages when the spring 25 is unwound.

The means for rewinding the spring motor consist of a collar 34 loosely mounted on the shaft and provided with a notched arm 80 35, as best seen in Fig. 4. This arm engages and is guided by the vertical guide rod 32. A spiral spring 52 is secured at one of its ends to arm 35 and at its other end to the hub of arm 33. This spring is placed under 85 tension as soon as arm 33 is moved out of engagement with guide rod 32, when the brushes 11 are rotated. A link 36 is attached at one end to collar 34, and its other end is pivotally attached to arm 37 of a bell 90 crank 38 which is pivoted to the frame. The other arm of the lever 38 is pivotally attached at 40 to a horizontally movable arm 41, which terminates in a hook 42. This arm 41 is provided with an integral up- 95 standing lug 43, the purpose of which will be hereinafter described. The longitudinal movement of the member 41 is guided by slotted link 44, which is secured to the frame. A spiral spring, the ends of which are 100 secured respectively to the link 44 and the frame of the switch, tends to move the mem-

ber 41 in a vertical direction whenever this element is free to move. The hook 42 of member 41 is adapted to engage a lug 47 carried by a bar 48. This bar is mounted 5 for intermittent or continuous reciprocating motion generated by a motor or any other source of power not shown in the drawings. If it is desired that bar 48 have reciprocating motion only when one of the switches 10 is unwound, the motor may have its operating circuit closed by contact springs 60, which are brought into engagement by the shaft 10 when it reaches its lowermost position.

15 49 designates the escape magnet whose armature 50 carries the movable escapement elements 51 of well-known structure, which control the escapement of triangular projection 53 carried by the arm of a pivoted 20 block 54 of the side switch. Brushes 55 carried by block 54 engage contacts 56 to complete switch-operating circuits which are well-known to those skilled in the art. The side-switch block 54 carries a tensioned pawl 25 57 which engages with the upstanding lug 43 to move the side switch into its normal position when the switch is being restored to normal.

30 The restoration of the switch to its normal position is accomplished as follows: The release magnet 29 is energized to attract its armature 28, thus withdrawing its pin 27 from the spiral groove of the cylindrical member 22. The cylindrical member then 35 rotates on the shaft to release the tension stored up in spring 25. The coil spring 52 then rotates the shaft and the cylindrical member which it carries, until the pawl 58 supported by the frame encounters notch 59 40 in the flange 23 of the cylindrical member, whereupon the shaft drops to released position. The shaft in its lowered position causes hook 42 to engage lug 47 of the reciprocating bar 48. The movement of hook 42 through the agency of the bell-crank lever operates to elevate the cylindrical member 22 and wind up spring 25. The shaft 10 will be elevated with the cylindrical member 22 until the uppermost tooth 45 50 of the vertical ratchet 14 is engaged by the vertical escapement member 15. As the member 22 is raised, it is also rotated to wind up the spring 25 when the pin 27 rides in the spiral groove of member 22. 55 The pawl 58 engages the flange 23 of the cylindrical member to hold the shaft elevated in its normal position.

60 It should be noted that the escapement member 15 and the uppermost vertical ratchet tooth are sufficiently spaced to permit slight upward movement of the shaft, due to the hook 42 riding over lug 47 whenever the switch is released on the return stroke of rod 48.

The present disclosure is merely illustrative of applicant's invention, and the device herein shown is capable of many modifications and variations which will be suggested to those skilled in the art, limited only by the appended claims.

70 What is claimed is:

1. In a selecting switch, passive contacts, active contacts, an element carrying said active contacts mounted for movement in two directions, a spring motor for operating 75 the brush carrying element in its several selecting movements, means for controlling these movements, and means for restoring said element to normal position.

2. In a selecting switch, passive contacts, 80 active contacts, an element carrying said active contacts mounted for movement in two directions, a spring motor for moving said brush carrying element through its several selecting movements, means for controlling the direction of these movements, and means for energizing said motor.

3. In a selecting switch, passive contacts, active contacts, a shaft carrying said active contacts, said shaft being mounted for vertical and rotary movements, a spring motor for actuating said shaft in its several selecting movements, means for controlling these movements, means for releasing said shaft, and means for restoring said motor and controlling means to normal position.

4. In a selecting switch, passive contacts, active contacts, a shaft carrying said active contacts, said shaft being mounted for vertical and rotary movements, a spring motor 100 for actuating said shaft in its several movements, means for controlling these movements, means for releasing said shaft, and means for rewinding said spring motor.

5. In a selecting switch, passive contacts, 105 active contacts, a shaft carrying said active contacts, said shaft being mounted for vertical and rotary movements, a motor for actuating said shaft in its several movements, directly operated escapement 110 means for governing said movements, means for controlling said escapement means, means to release said shaft, and means to restore said motor and escapement-controlling means to normal position.

115 6. In a selecting switch, passive contacts, active contacts, a shaft carrying said active contacts, said shaft being mounted for vertical and rotary movements, a motor for actuating said shaft in its several movements, directly operated vertical escapement means, and directly operated rotary escapement means for governing said movements, means for controlling said vertical and rotary escapement means, means to release said shaft, and means to restore said motor and escapement-controlling means to 120 125 normal position.

7. In a selecting switch, passive contacts, active contacts, an element carrying said active contacts mounted for movement in two directions, a single spring for operating said element in its several selecting movements, means for controlling these movements, and means for restoring said element to normal position.

In witness whereof, I hereunto subscribe my name this 11th day of October, A. D., 1916.

CHARLES L. GOODRUM.

In witness whereof, I hereunto subscribe my name this 27 day of Sept., A. D., 1916.

JOHN A. KROPP.
